(57) **CLAIM**

The ornamental design for a back support for a chair, as shown and described.

DESCRIPTION

FIG. 1 is a front perspective view of the back support for a chair embodying the new design;

FIG. 2 is a rear perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

FIGS. 1-8 show a seat support in broken lines. The portions shown in broken lines are for environmental purposes only and form no part of the claimed design.

1 Claim, 7 Drawing Sheets
